UNITED STATES PATENT OFFICE.

JOHN T. CLARK, JR., OF BROOKLYN, NEW YORK.

FAUCET.

1,320,446.

Specification of Letters Patent.

Patented Nov. 4, 1919.

Application filed April 29, 1919. Serial No. 293,481.

To all whom it may concern:

Be it known that I, JOHN T. CLARK, Jr., a citizen of the United States, residing at Brooklyn, county of Kings, and State of 5 New York, have invented a certain new and useful Improvement in Faucets, of which the following is a specification.

This invention relates to cocks or faucets, and the object of the invention is to provide 10 improved means for holding the valve disk in operative relation to the hand operated plug of the faucet.

Faucets have long been employed, and have been constructed with valve disks, usually 15 of leather or composition material, which have been held to the movable plug of the faucet by means of a screw passed through the disk and threaded into the plug. Because of the fact that this screw is constantly 20 subjected to the action of the liquid, the flow of which the faucet controls, said screw unvariably becomes corroded so that it not infrequently breaks when its removal is attempted. In all events, the head of the 25 screw so badly deteriorates under the corrosive action referred to, that its removal by a screw-driver, as intended, is generally impossible, and gas pliers or wrenches are usually resorted to.

30 The object of the present invention is to provide means for holding the disk in position, independently of screw threads, and through a simple push connection, whereby the disk is frictionally held in place, and 35 corrosive action will not render its removal arduous or difficult.

In the preferred embodiment of the invention the disk is provided with a cup or thimble adapted to be manually forced into 40 a pocket in the plug, and maintained in such position by friction, as well as the fact that any attempt by the thimble to leave the pocket will produce a partial vacuum which will serve to hold the thimble against removal.

45 Features of the invention other than those specified will be apparent from the herein-after detailed description taken in conjunction with the accompanying drawings.

50 In the accompanying drawings I have illustrated one practical embodiment of the invention, but the construction shown therein is to be understood as illustrative only, and not as defining the limits of the invention.

Figure 1 is a section of a faucet showing

the present invention as applied thereto; and

Fig. 2 illustrates the present invention removed from the faucet.

Referring to the drawings A indicates a faucet provided with the usual screw plug B adapted to be operated by a handle C, associated with the stem b of the plug, for the purpose of raising and lowering the plug for 60 seating or unseating the valve, as desired. The faucet is further provided with the usual feed duct D and the outlet duct E between which is a valve passage F peripherally of which is formed a valve seat f.

I designates a thimble open at its top and closed at its bottom except for a central aperture through which a bolt H is adapted to be passed, the head of the bolt seats within the thimble and its shank extends downwardly and through the valve disk G. A washer g is slipped over the shank of the bolt below the disk and a nut H' is screwed on to the bolt to bind the parts together. The hole in the disk, through which the bolt 70 passes preferably fits the bolt rather tightly so that in installing the disk initially, it is screwed to the threads of the bolt and the washer G and nut H' thereafter applied.

The thimble I may be made of any suitable material, but is preferably resilient so that it may be readily manually forced into a hole or pocket J drilled into the bottom of the plug B and adapted to receive said thimble for attaching the disk G to the plug. In 80 attaching, the thimble is merely pressed into the pocket J so as to frictionally engage with the walls thereof after the manner shown in Fig. 1.

Through the mounting of the disk as described, it will appear that during the operations of the plug the disk is free for rotary movement relative thereto, and may thus remain stationary during rotation of the plug B. This is a decided advantage, since the 90 disk G will not be forcibly ground against the valve seat and worn out through such operation as is now generally the case where the disk is rigidly screwed to the plug. When it is desired to replace the disk with 100 a new one, it is only necessary to grasp the disk and withdraw the thimble I, the restraining power of said thimble being insufficient to withstand such a manually applied pull though entirely sufficient to normally 110 hold the disk in position.

Having thus fully described the invention,

what I claim as new and desire to secure by Letters Patent is:

1. A valve embodying a valve seat, a plug movable toward and away from the seat, which plug is provided in the end thereof adjacent the seat with a pocket, a valve disk positioned adjacent the pocketed end of the plug and adapted to coöperate with the valve seat, and a thimble having rotatable connection with the valve disk and resiliently and frictionally held within the pocket of the plug for the purpose of mounting the disk for movement with the plug toward and away from the valve seat.
- 15 2. A valve provided with a seat, a valve plug movable toward and away from the seat and provided in the end thereof adjacent the seat with a cylindrical pocket, a cylindrical thimble closed at its outer end and seated in said pocket, a valve disk positioned between the plug and the seat, and a bolt passing through the closed end of the

thimble and through the valve disk for mounting the disk on the plug for longitudinal adjustment relative thereto and for movement therewith toward and away from the seat.

3. A valve provided with a seat, a valve plug movable toward and away from the seat and provided in the end thereof adjacent the seat with a cylindrical pocket, a cylindrical thimble closed at its outer end and positioned within said pocket and frictionally engaging the walls thereof, a bolt secured to the thimble and provided with a threaded shank, a valve disk screwed upon said threaded shank, and a nut screwed on to said shank after the valve disk for locking the disk to the bolt, whereby the valve disk is mounted on the plug for movement toward and away from the seat.

In testimony whereof, I have signed my name to this specification.

JOHN T. CLARK, JR.
